UNITED STATES PATENT OFFICE.

JOSEPH J. WHITE, OF CRANSTON, RHODE ISLAND, ASSIGNOR TO J. J. WHITE MANUFACTURING COMPANY, OF PROVIDENCE, RHODE ISLAND.

DESIGN FOR A GEM.

Application filed March 11, 1925. Serial No. 12,681. Term of patent 14 years.

To all whom it may concern:

Be it known that I, JOSEPH J. WHITE, a citizen of the United States, residing at Cranston, in the county of Providence and State of Rhode Island, have invented a new, original, and ornamental Design for a Gem, of which the following is a specification, reference being had to the accompanying drawing, forming part thereof.

Figure 1 is a top view of a stone cut to embody the invention.

Figure 2 is a side elevation thereof.

Figure 3 is an end elevation.

Figure 4 is a cross section of the stone.

Figure 5 is a longitudinal section.

Figure 6 is a bottom view of the stone.

The contour of the stone as viewed from the top is an important element of the invention.

I claim:

The ornamental design for a gem, as shown.

JOSEPH J. WHITE.
